United States Patent Office

Des. 215,922
Patented Nov. 11, 1969

215,922

BOTTLE COVERING

David M. Marsh, 14 Capri Drive, Roslyn, N.Y. 11576

Filed Sept. 26, 1968, Ser. No. 13,726

Term of patent 14 years

Int. Cl. D9—06

U.S. Cl. D9—250

Fig. 1.

Fig. 3.

Fig. 2.

Fig. 4.

Fig. 5.Fig. 7.Fig. 6.Fig. 8.FIG. 1 is a front view, slightly in perspective, of a bottle covering embodying my new design;

FIG. 2 is a rear view slightly in perspective;

FIG. 3 is a top plan view; and

FIG. 4 is a bottom plan view thereof;

FIG. 5 is a front view, slightly in perspective, of another embodiment of my new design;

FIG. 6 is a rear view slightly in perspective;

FIG. 7 is a top plan view; and

FIG. 8 is a bottom plan view thereof.

The broken lines showing a bottle are for illustrative purposes only.

I claim:

The ornamental design for a bottle covering, substantially as shown and described.
